[57] CLAIM

The ornamental design for an ejecting and retaining catch for printed circuit board sleeves, as shown and described.

DESCRIPTION

FIG. 1 is a bottom, front, and left side perspective view of an ejecting and retaining catch for printed circuit board sleeves showing my new design;

FIG. 2 is a top, rear, and left side perspective view thereof;

FIG. 3 is a reduced front elevational view thereof;

FIG. 4 is a reduced right side elevational view thereof, the left side being a mirror image of that shown;

FIG. 5 is a reduced rear elevational view thereof;

FIG. 6 is a reduced top plan view thereof; and,

FIG. 7 is a reduced bottom plan view thereof.

FIG. 1

FIG. 2

FIG. 6

FIG. 3
